UNITED STATES PATENT OFFICE

2,433,806

PROCESS FOR MAKING CONTAINERS

Georges Bardin, Tournus, Saone-et-Loire, France

Application February 5, 1938, Serial No. 188,873
In France March 10, 1937Section 3, Public Law 690, August 8, 1946
Patent expires March 10, 1957

1 Claim. (Cl. 113—120)

1

The present invention relates to a process for constructing thin-walled hollow bodies by stamping.

Containers are known which consist of a stiff and of a flexible cap, the latter of which is pressed inwards into the former for emptying the contents. The manufacture of such containers according to the known processes is difficult and costly. If the cap is manufactured from a thin sheet of aluminum or the like by stamping, folds or cracks are formed in the sheet, the distribution of the thickness is irregular, the container is porous and leaky, the cap has to be provided with a coating, whereby the cost of manufacture is increased.

On the other hand, it is necessary in the known processes, to lubricate both faces of the sheet before stamping, so that after stamping it is necessary to clean the inner wall of the cap; this is particularly difficult and costly for the flexible inner wall.

The process according to the invention, which eliminates these drawbacks, consists in stamping the thin cap of the container simultaneously with the stiffer cap; a nozzle or nozzle support may be provided beforehand in the rigid sheet.

Owing to this simultaneous stamping, on the one hand the resistance to stamping is increased and on the other hand the friction between the stamping tool and the thin sheet to be stamped is eliminated on one side, whereby excessive stresses on the thin sheet are prevented and a flawless fluid-tight container wall is produced.

In the accompanying drawing examples of embodiments of the object of the invention are shown. In said drawing:

Fig. 1 is a diagrammatical view of a container in section;

Fig. 2 shows a container manufactured according to the present process, before filling;

Fig. 3 is a diagrammatical view of an apparatus for carrying out the process according to the present invention;

Fig. 4 shows an embodiment of the device for manufacturing a container according to Fig. 1.

According to Fig. 3, the thin metal sheet to be stamped 5 together with a protecting plate 6 is placed on the tool, for example the sheet 5 to be shaped resting on the die 7 and the punch 8 which is guided by the parts 8a acting on the protecting plate 6 which is in general thicker than the metal sheet 5 to be shaped. Owing to the use of the protecting plate 6 which acts as a damper, and procures a uniform distribution of

the stamping stress over the entire surface of the sheet 5 and eliminates the friction of the punch 8, a correct shape of the hollow body is obtained. The container wall thus manufactured 5 has neither perforations, cracks, porosities nor leaks.

The protecting plate 6 which serves as a lining can be made of any appropriate material and have any appropriate thickness, it may for example be made of the same metal as the sheet to be shaped, any device being used which facilitates the subsequent removal of the protecting plate 6.

If elements are shaped which are to form the 15 same assembly, according to the present process the two sheets are shaped simultaneously. If for example a container is to be manufactured which, as shown in Fig. 1, consists of a stiff half-container provided with a nozzle support 2 and of which the periphery is fixed by fluid-tight crimping to the periphery of a flexible cap, the simultaneous stamping of the elements 1 and 20 4 is effected in the manner shown in Fig. 4.

The stiffer plate 9 from which the cap 1 is 25 formed and in which the depression 10 serving as a nozzle support has already been provided, is placed on the die 11 in the presence of an intermediate die 12 which is supported by a spring 13 in order to prevent the deformation of the nozzle during the stamping operation, then the plate 9 is laid on a thin metal sheet 14 and the whole arrangement is subjected to the pressure of the punch 15 guided by the parts 17.

In this manner, when the stamping is completed and the edge 3 of the stiff cap has been crimped on the periphery 4 of the flexible cap by the die 16 in conjunction with the die 11, the container shown in Fig. 2 is obtained. The 30 stamping is effected without any lubrication of the contacting faces of the sheet, whereby a subsequent cleaning is eliminated.

The container takes up its final shape shown in Fig. 1 during the filling under pressure with the contents to be stored in the container.

Containers of any desired shape can be manufactured according to the process described. The wall of the hollow bodies can be provided with a lining or a protecting covering made of non-corrodible metal or of precious metal as an ornamentation, by simultaneously stamping a thin sheet of non-corrodible or precious metal. The process can also be used for manufacturing containers of all kinds, in particular for shaping appropriate substances by stamping.

2

What I claim as new and desire to secure by Letters Patent, is:

A process for manufacturing containers consisting in placing a relatively flexible flat metal sheet in face to face contact with the flat portions of a relatively rigid flat metal sheet having a nozzle performed thereon, simultaneously die-shaping the contacting flat portions of the two sheets in one shaping operation to produce from each sheet a dome-shaped structure, the two dome-shaped structures being in face to face contact in their simultaneously shaped portions, and joining the edges of the two contacting dome-shaped structures, at least a part of the central portions of the flexible structure being adapted to be separated from the relatively rigid structure to form a container.

GEORGES BARDIN.
